**OVERLOAD AND SHORT CIRCUIT PROTECTOR
FOR TRANSISTOR VOLTAGE REGULATOR**
David L. Decker, Cedar Rapids, Iowa, assignor to Collins
Radio Company, Cedar Rapids, Iowa, a corporation of
IowaFiled Mar. 31, 1960, Ser. No. 18,922
1 Claim. (Cl. 323—22)

This invention relates to an overload and short circuit protector device and more particularly to a device for use in voltage and current regulators of the type utilizing semi-conductors to protect the components of the regulator against damage due to heavy overloads or shorts in the output circuit of the regulator.

Voltage and current regulators are well known in the art and in the past commonly utilized at least one power amplifying tube to provide the desired regulated output. While it was desirable to protect the regulator, and especially the power tube, against damage, which sometimes required the use of protector devices, the necessity of such a protector device has been accentuated in recent years due to the development and use of semi-conductors in voltage and current regulators. This is due to the fact that a semi-conductor is far more susceptible to severe damage due to the heat produced during excessive conduction of current than is a vacuum tube.

Various protector devices have heretofore been suggested and utilized to protect the components, and especially the semi-conductors, used in the voltage and current regulator against damage due to a short in the output circuit since this obviously would cause heavy current conduction through the regulator and damage its components severely in a very short time.

Providing a protector device that merely guards against a short in the output circuit, however, is not sufficient, of itself, to adequately protect a voltage and current regulator since a short in the output circuit is only one possible occurrence which can cause damage to the regulator. An additional, and very real possibility of damage, also exists in the event that a heavy overload is connected into the output circuit of the regulator, since this too will cause excessive current conduction therethrough.

It is therefore an object of this invention to provide simple, yet reliable means to protect a voltage and current regulator against damage due to either a short or a heavy overload in the output circuit of the regulator.

It is another object of this invention to provide means responsive to the regulator output voltage to bias the power amplifier of the regulator to cutoff whenever a heavy overload or short appears in the output circuit of the regulator to thereby protect said regulator against damage due to excessive current flow therethrough.

More particularly it is an object of this invention to provide protector means including a transistor normally biased to cutoff so that said means is operable only when the regulated output voltage of the regulator drops below a predetermined and preset level to thereafter preclude further conduction of current through the regulator.

It is still another object of this invention to provide protector means operable to preclude current flow through the regulator after a heavy overload or short is connected into the output circuit of such a regulator and to maintain said regulator in its inoperative state until such time as the heavy overload or short is removed from the output circuit and the input signal to the regulator is thereafter removed and then reapplied.

With these and other objects in view which will become apparent to one skilled in the art as the description proceeds, this invention resides in the novel construction, combination and arrangement of parts substantially as hereinafter described and more particularly defined by

2

the appended claims, it being understood that such changes in the precise embodiments of the herein disclosed information may be submitted as come within the scope of the claims.

5 The accompanying drawings illustrate two complete examples of two embodiments of the invention constructed according to the best mode so far devised for the practical application of the principles thereof, and in which:

10 FIGURE 1 is a schematic circuit diagram of a voltage and current regulator having the protector device of this invention incorporated and illustrated as a part thereof; and

15 FIGURE 2 is a schematic circuit diagram of a modified voltage and current regulator having a modified protector device incorporated and illustrated as a part thereof.

20 Referring now to the drawings in which like numerals have been used to identify like characters throughout, the numeral 3 designates generally a voltage and current regulator, which may be of conventional type, in which the protector device 4 of this invention may be utilized to protect the regulator against damage should a short circuit or a heavy overload be connected into its output circuit.

25 As shown in FIGURE 1, voltage and current regulating device 3 may include a power amplifier 6, which is preferably a transistor, and signal sampling means 7 to regulate the conduction of transistor 6 by controlling the bias thereof.

30 As shown in the drawings, transistor 6 may be of the PNP type (as shown in FIGURE 1) or of the NPN type (as shown in FIGURE 2 and designated with the numeral 106) so long as other circuitry of the regulator is changed accordingly as brought out more fully herein-after.

35 As shown in FIGURE 1, transistor 6 may have its emitter connected with the positive output of a source of unregulated direct current signal 8 by means of a lead 10, its collector connected with a variable output circuit load 12 by means of regulated output circuit lead 14, and its base connected with the negative output of source 8 through bias resistor 16 by means of leads 18 and 19 which are connected to ends 20 and 21, respectively of bias resistor 16. To complete the output circuit, load 12 may also be connected to lead 19 by means of lead 22. If desired, stabilizing capacitor 23 may be connected across output leads 14 and 22 to prevent oscillation.

40 Signal sampling means 7, as above stated, regulates the bias on transistor 6 to thereby control the conduction of the same so that a regulated output is supplied by the regulator. As shown by the drawings, signal sampling means 7 includes a voltage divider 25 which may include a fixed resistor 26 and a variable resistor 27 serially connected between leads 14 and 22. As shown in FIGURE 1, the variable tap 28 of resistor 27 may be connected to the base of a transistor 30 of the NPN type through current limiting resistor 31 and diode 32, which is, of course, connected so that low resistance is offered to base current flow.

45 The emitter of transistor 30 is connected to leads 19 and 22 through a breakdown junction or Zener diode 35, which diode is also connected to input lead 10 through bias resistor 36. Diode 35 is orientated so that the voltage applied to the emitter of transistor 30 is maintained at the breakdown voltage of the diode.

50 The collector of transistor 30 is connected to the base of a PNP type transistor 40 through current limiting resistor 41 while the collector of transistor 40 is, in turn, connected to side 20 of resistor 16, which, as brought out hereinbefore, provides bias for transistor 6. The emitter of transistor 40 is directly connected to input lead 10 by means of leads 45 and 46, and resistor 16 is therefore

also in the output circuit of transistor 40. Forward bias for transistor 40 is provided by resistor 48 which connects the emitter and base of said transistor.

The protector device 4 of this invention includes a voltage divider 53 which may include fixed resistance 54 and variable resistance 56, the variable tap 57 of which may be directly connected to the base of a PNP type transistor 60, as shown in FIGURE 1. The emitter of transistor 60 may be connected with input lead 10 through resistor 62 and connecting leads 46 and 63. A breakdown junction or Zener diode 64 is connected between leads 19 and 63 to maintain the voltage of the emitter of transistor 60 at the breakdown voltage of the diode. In addition, a capacitor 65 is connected in parallel with diode 64, and this capacitor along with resistor 62 provides an R.C. time constant the purpose of which is hereinafter brought out.

The collector of transistor 60 is connected to the base of transistor 30 through limiting resistor 66 and due to the orientation of diode 32, collector circuit current must be applied to the base of transistor 30, the result of which is to bias transistor 6 to cutoff as brought out hereinbelow.

In operation, the voltage and current regulator shown in FIGURE 1 normally operates in the following manner. Assuming that the load 12 is increased by an amount not considered excessive, the voltage potential between leads 14 and 22 will decrease thus decreasing the voltage drop across voltage divider 25. This means that a lower, or more negative, voltage is impressed upon the base of transistor 30, and since it is a transistor of the NPN type, conduction in the base circuit decreases causing a corresponding decrease in conduction in the collector circuit. This decrease in current flow, of course, causes a decrease in the voltage drop across bias resistor 48 which is in the collector circuit of transistor 30. The decreased voltage drop across resistor 48 causes the emitter of transistor 40 to become less positive with respect to the base so that conduction in the base-emitter circuit of PNP type transistor 40 is decreased. The collector current of transistor 40 will, of course, likewise be decreased, and since resistor 16, which provides bias for transistor 6, is also in the collector circuit of transistor 40, there will be a decrease in the voltage dropped across this resistor. This decreased voltage drop across resistor 16 is impressed upon the input circuit of transistor 6 so that the base of transistor 6 becomes less positive, or more negative, than the emitter, and results in increased conduction by transistor 6.

When the output voltage of the regulator is substantially returned to its former level, the bias of transistor 6, which is controlled by the output level, will, of course, be altered accordingly to decrease the conduction of transistor 6 to maintain the output at a predetermined regulated level.

The protector device of this invention is normally inoperative during the above described normal operation of the regulator since this protective network is needed only in case of a heavy overload or a short in the output circuit. This is accomplished by biasing transistor 60 to cutoff for normal operation by adjusting variable tap 57 of resistor 56 (which is a part of voltage divider 53) so that a higher positive voltage is impressed upon the base of PNP type transistor 60 than is present on the emitter. Thus the protector device can be preset to become operative at any predetermined output potential by adjusting variable tap 57.

From the foregoing it will be appreciated that the protector device of this invention will be inoperative until the potential between output leads 14 and 22 decreases to a value that causes the voltage impressed upon the base of transistor 60 to be more negative than the emitter voltage.

When, for example, output circuit load 12 is increased to such an extent that it constitutes a heavy overload, the potential between leads 14 and 22 will be decreased causing a corresponding decrease in voltage drop across di-

viders 25 and 53. It is to be noted that the same decrease in voltage drop across these dividers occurs in the case of a short circuit although it is usually much more pronounced and acts to short out the dividers completely. When such a heavy overload or short appears in the output circuit of the regulator, the regulator normally tries to supply the necessary voltage to return the output to its former level. This, of course, can cause excessive conduction and severe damage through excessive heat to the components of the regulator and especially to the power transistor. The protector device of this invention prevents this excessive conduction in the following manner.

When a heavy overload or a short first appears in the output circuit, transistor 60, which, as brought out hereinbefore is normally biased to cutoff, will immediately start to conduct because of the decreased voltage impressed upon its base to make it negative with respect to the emitter. Collector current from transistor 60 is applied to the base of transistor 30 causing the base of NPN type transistor 30 to become more positive with respect to the emitter. This causes transistor 30 to conduct at an increased rate and causes a greater voltage drop across resistor 48, which, in turn causes the emitter of PNP type transistor 40 to become more positive with respect to the base. This causes transistor 40 to conduct at an increased rate and causes a greater voltage drop across resistor 21 which, in turn, causes a greater voltage to be impressed on the base of transistor 6 biasing the same to cutoff and thereby rendering the regulator inoperative.

When protector device 4 is caused to operate and bias transistor 6 to cutoff, the voltage regulator will remain inoperative until such time as the input voltage is removed from the regulator. When this voltage is reapplied the R.C. time constant provided by resistor 62 and capacitor 65 is such so as to allow the output to build up and bias transistor 60 to cutoff before full voltage is applied to the emitter of transistor 60. If, of course, the heavy overload or short circuit has not been removed, however, the protective device will again immediately bias transistor 6 to cutoff and render the regulator inoperative.

It is to be appreciated that the protector device of this invention may be modified by using a transistor of the NPN type, if the circuitry of the voltage and current regulator in which it is utilized so requires, without departing from the spirit or scope of this invention.

FIGURE 2 illustrates, for example, a voltage and current regulator 103 utilizing a transistor of the NPN type in place of PNP type transistors 6 and 40 and a PNP type transistor in place of NPN type transistor 30 as shown in FIGURE 1. The protector device 104 in this case may utilize a transistor of the NPN type in place of the PNP type transistor 60 as shown in FIGURE 1.

As shown in FIGURE 2, a negative lead 110 is connected to the emitter of transistor 106 while positive lead 119 is connected to the emitter of transistor 106 while positive lead 114 is connected to the base of transistor 106. In addition, lead 114 is a negative output circuit lead and is connected with the collector of transistor 106, while lead 122 is the positive output circuit lead and is connected to lead 119. It can therefore be readily appreciated that the circuit will operate in much the same manner as that of FIGURE 1, but the voltage polarities will be reversed. For this reason, Zener diodes 35 and 64 must, of course, be reversed and the same is true of diode 32.

In operation, when an increased load, not considered excessive, is applied to output circuit load 12, the voltage potential between leads 114 and 122 will be decreased. This, of course, causes a decrease in voltage drop across voltage divider 25 and causes a decrease in the voltage applied to the base of PNP type transistor 130. It is to be remembered, however, that the emitter of transistor 130 is also negative so that a decrease in negative voltage on the base decreases the difference in potential between

the emitter and base. This causes a decrease in conduction in the input circuit and will, therefore, decrease current conduction in the collector circuit. This causes a decrease in the voltage drop across bias resistor 48 and because of the polarity of this voltage drop makes the emitter of NPN type transistor 140 less negative with respect to the base and causes decreased conduction in its output circuit. This, in turn, causes a decreased voltage drop across bias resistor 16 and, due to the polarity of this voltage drop, the voltage impressed upon the base of NPN type transistor 106 makes the base less negative, or more positive, with respect to the emitter and causes increased conduction in the output circuit to return the voltage potential between output leads 114 to 122 to the desired level.

If, however, a short or a heavy overload is connected into the output circuit of the regulator, protector device 104, which has been modified by replacing the PNP type transistor shown in FIGURE 1 with a transistor of the NPN type as brought out hereinabove, will conduct to bias transistor 106 to cutoff and render the regulator inoperative. This is accomplished by applying the collector current of transistor 160 to the base of transistor 130 in the same manner as that described in connection with the protector device shown in FIGURE 1. This impressed voltage causes increased conduction in PNP type transistor 130, which in turn causes increased conduction in transistor 140. The resulting increased voltage drop across resistor 16 impresses a more negative voltage on the base of NPN type transmitter 106 and causes the same to be biased to cutoff.

As described in connection with FIGURE 1, the regulator shown in FIGURE 2 will likewise remain in a non-operative state until such time as the input signal from source 9 is removed from the input leads 110 and 119 and then reapplied since the emitter of transistor 160 will remain more negative than the base until the signal is first removed from this emitter.

While two specific examples have been shown and illustrated herein to adapt the protector device of this invention to a specific voltage and current regulator, it is to be appreciated, of course, that the protector device of this invention might be modified to meet other specific circuitry requirements without departing from the spirit or scope of this invention.

In view of the foregoing it should be obvious to those skilled in the art that the protector device of this invention provides simple yet reliable means for protecting a voltage and current regulator against damage to its com-

ponents from excessive conduction through the regulator due to a heavy overload or a short in the output circuit of the regulator.

What is claimed as my invention is:

5 A transistorized voltage and current regulating device of the type having output overload and short circuit protector means and requiring no operating power other than that from an unregulated D.C. source, said regulating device comprising: power amplifying means having an input circuit and an output circuit, said input circuit including resistance means for biasing said power amplifying means and said output circuit including voltage divider means; means adapting said input circuit for connection with an unregulated D.C. power source; means 10 adapting said output circuit for connection with a load so that said load is in parallel with said voltage divider means; output voltage sampling means connected between said voltage divider means and said resistance means to determine and regulate the bias on said power 15 amplifying means; a transistor having an input electrode, a control electrode, and an output electrode; a Zener diode connected with said input circuit and with said input electrode for assuring that a constant voltage is applied to said input electrode; means for applying direct 20 voltage from said voltage divider means to said control electrode to normally bias said transistor to cutoff, said transistor remaining in a nonconductive state until a load connected with said output circuit draws excessive current causing said transistor to conduct, said transistor then remaining in said conductive state until the power from the unregulated source is removed; means connecting said output electrode with said voltage sampling means for coupling an output signal thereto while said transistor is in a conductive state to bias said power amplifying 25 means to cutoff; and an R.C. network including a capacitor in parallel with said Zener diode and a resistor having one end connected to said input electrode and the other end connected to said input circuit whereby said 30 R.C. network prevents the application of breakdown voltage to the input electrode of said transistor for a predetermined time interval immediately after power from the unregulated source is coupled to said regulating device to thereby allow cutoff bias to first be impressed upon the control electrode of said transistor.
